UNITED STATES PATENT OFFICE

CHARLES HEATH MENDENHALL, OF HOMER, LOUISIANA

CANT HOISTER

Application filed March 26, 1930. Serial No. 439,145.

This invention aims to provide novel means for putting logs on a saw mill carriage, to be sawed into timbers, and to provide novel means for turning the logs, as the slabs of timber are cut off. Other objects of the invention are to supply novel means for raising the timber after it has been sawed into shape, it being possible to hold in reserve the timbers which have been sawed, so that other operations may be performed upon them, the reserve timbers being lowered when occasion requires.

It is within the province of the disclosure to improve generally and to enhance the utility of devices of that type to which the present invention appertains.

With the foregoing and other objects in view, which will appear as the description proceeds, the invention resides in the combination and arrangement of parts and in the details of construction hereinafter described and claimed, it being understood that changes may be made in the precise embodiment of the invention herein disclosed, within the scope 25 of what is claimed, without departing from the spirit of the invention.

In the accompanying drawings:—

Figure 1 shows in elevation, a device constructed in accordance with the invention; 30 Figure 2 is an elevation wherein the structure is viewed at right angles to the showing of Figure 1.

The numeral 1 marks the tracks on which moves the carriage 2 that carries logs 9 to a saw 3, the logs resting against an abutment 4 on the carriage 2, the resulting product being a completed timber which is shown at 5. The saw 3 is carried by a shaft 6, or otherwise, the shaft being journaled for rotation on the foundation 7. The skids that carry the logs down to the carriage 2 are marked by the numeral 8, and the logs, as aforesaid, are designated, by the numeral 9.

A frame 11 is provided. A horizontal shaft 12 is journaled in bearings 14 on the frame 11 and is prevented from moving endwise by collars 15. One end of a flexible element 16 is wound about the shaft 12, the flexible element being continued over pulleys 17 on the frame 11. On the depending lower

end of the flexible element 16 is mounted a counter weight 18.

A large beveled pulley 19 is connected by a clutch 20 to the shaft 12, and the clutch 20 is under the control of a lever 21 fulcrumed on any accessible part of the frame 11. 55

Friction pulleys 22 are mounted on a shaft 27 which is driven by a belt 28 and pulleys 29 and 30 from the saw shaft 6. The pulleys 22 are under the control of a yoke 23, so that either of the pulleys 22 may be brought into engagement with the large pulley 19, the yoke 23 being mounted to slide on the shaft 27. A link 24 is pivoted to the yoke 23 and is pivoted to a bell crank lever 25 that is fulcrumed on the frame 11. A depending handle 26 is pivoted to the bell crank lever. 60

Flexible elements 31 are wound on the shaft 12 and carry dogs 32 at their lower ends, the dogs 32 being adapted to be set into the logs 9 on the skids 8. 70

Through the instrumentality of the handle 26, the bell crank lever 25, the link 24, and the yoke 23, the appropriate one of the pulleys 22 may be brought into frictional engagement with the large pulley 19. There is then established a driving chain comprising the pulley 10, the shaft 6, the pulley 30, the belt 28, the pulley 29, the shaft 27, the appropriate one of the pulleys 22, the large pulley 19, and the shaft 12, the flexible elements 31 being reeled on the shaft 12 and the log 9 being lifted on the carriage 2, into engagement with the abutment 4. 75

When the carriage 2 is reciprocated, the saw 3 will cut a slab off the log. It is then necessary to turn the log over, so as to have another slab cut off it. This can be done by means of the flexible elements 31 and the dogs 32, the yoke 23 being shifted, of course, to bring about a reversal in the direction of rotation of the shaft 12, whenever necessary. 85

The general construction is such that much heavy peavey work will be done away with and when the log is squared up to make the timber shown at 5, the timber, or several timbers, may be hoisted away, and supported on suspension elements or hooks 33, which are hingedly mounted on the frame 11, it 100

being possible to hold several sawed timbers in reserve, so that further operations may be performed on them, or for any other purpose.

- 5 In the event that the operator does not wish to use the device for some considerable period of time, there is no reason for having the large friction pulley 19 in rotation. Under such circumstances, the lever 10 21 is operated to disconnect the clutch 20, so that the pulley 19 will be disconnected from the shaft 12. When the clutch 20 is thrown out, the shaft 12 will be rotated by means of the flexible element 16 and the 15 weight 18, to unwind the chains 31 from the shaft 12, and the lower the dogs 32 into position to be engaged with the log.

The pulleys 22 may be so shifted with respect to the pulley 19 that neither of the 20 pulleys 22 will engage the pulley 19, and, then, the shaft 12 will remain at rest; or either of the pulleys 22 may be brought into engagement with the pulley 19, to secure a direct rotation of the shaft 12, or a reverse 25 rotation of the said shaft.

The device forming the subject matter of this application is simple in construction, but it will dispense with much heavy peavey work, around a saw mill, and will make it 30 possible to operate the mill with fewer laborers. The output of the mill will be increased, also.

Having thus described the invention, what is claimed is:

- 35 In a device of the class described, a track, a sawmill carriage movable along the track, a saw at the side of the sawmill carriage, a foundation, skids carried by the foundation and leading to the saw, a saw arbor 40 carrying the saw and journaled on the foundation, the saw arbor being disposed at right angles to the tracks and to the saw, a frame upstanding above the skids, a first shaft disposed at right angles to the saw arbor and 45 journaled on the frame, above the saw shaft, first flexible elements wound about the first shaft, log-engaging means carried by the flexible elements, in operative relation to the skids, a second flexible element wound 50 about the first shaft and operating counter to the first flexible elements, a weight attached to the second flexible element, a second shaft disposed at right angles to the first shaft and journaled on the frame, means for 55 rotating the saw arbor, an operative connection between the second shaft and the saw arbor, a first bevelled wheel loose on the first shaft, a clutch connecting the first bevelled wheel with the first shaft, a yoke slide- 60 able longitudinally on the second shaft, means under the control of an operator for sliding the yoke, bevelled wheels on the second shaft and movable, one at a time, by the yoke, into engagement with the first bevelled 65 wheel, and suspension elements on the frame,

above the carriage, the first flexible elements constituting turners for logs on the skids, and constituting means for hoisting a sawn timber from the carriage to the suspension elements.

In testimony that I claim the foregoing as my own, I have hereto affixed my signature.

CHARLES HEATH MENDENHALL.
